APPARATUS FOR WAVING HAIR

Jacob A. Kols, Columbus, Ohio

Application March 27, 1944, Serial No. 528,231

7 Claims. (Cl. 132—34)

My invention relates to an apparatus for waving hair. It has to do, more particularly, with an apparatus for stretching the hair from the tips to the scalp in such a manner that a better curl or wave is obtained.

In the past, various types of permanent waving methods and apparatus have been used for winding the hair preparatory to the heating operation. While this winding stretched the hair to a limited extent the full importance of the stretching was not realized. Furthermore, the art was not cognizant of the fact that stretched hair curls more easily and holds the curl longer. In present day permanent waving the scalp protector clamp has the hair drawn through it, and to stretch the hair very much during the winding on the mandril would loosen the roots and would also be very uncomfortable to the person obtaining the wave. The art, therefore, did not have a tool which would permit the tensioning of the hair longitudinally to the extent which I employ in my method. In the past, with regard to hair which is very fine, it was necessary to use a strong chemical solution for softening the hair previous to the winding and heating operations. The heat generates steam which sometimes burns the scalp of the person being worked on, and the longer the heat is left on the hair the more danger there is of injuring the hair as well as the person. This is also true when the scalp is under tension due to pulling on the hair, thus raising the skin of the scalp making it tender and more receptive to the forming of blisters.

Another object of my invention is to provide an apparatus for stretching the hair which will not pull on the scalp of the person being treated and will not loosen the roots of the hair.

Another object of my invention is to provide a hair stretching device in which the hair is stretched a number of times from the tip of the hair to the scalp before the heat is applied.

Another object of my invention is that I provide a hair stretching device which will be easy to operate and inexpensive to construct.

In its preferred form my invention comprises the method of curling the hair by stretching the hair at intervals or in short sections from the tips of the hair inwardly to the scalp. This method results in a much better curl, and the curl is more permanent than the usual type now obtained in present day permanent waving. The use of the natural resiliency of the hair in curling has two marked advantages over the prior art type of winding the hair from the tips

inwardly in that a much weaker solution can be used to soften the hair and less heating time is needed. All hair has a natural resiliency and I have found that when it is stretched it can be more readily curled. I provide an apparatus for stretching the hair of such a nature that there is no pull on the scalp. I accomplish this stretching by placing between the scalp and the winding mandril a pair of gripping members which hold the hair against movement while the winding is taking place, thus stretching the hair between the point of the gripping member and the winding mandril. Since there is no tension on the hair between the gripping members and the scalp I may stretch the hair to its greatest extent as it is being wound on the mandril. This stretching operation is repeated a number of times from the tips of the hair to the scalp, and thus as the hair is wound on the mandril it is stretched to its greatest extent throughout. I have found from actual experience that hair stretched in the manner set forth above will curl more easily and the heating time now needed to achieve a permanent wave is considerably reduced.

Various other objects and advantages will be apparent from the following description and the drawing wherein similar characters of reference are used to designate corresponding parts and 30 wherein:

Figure 1 is a top plan view of my curling device which is partly broken away.

Figure 2 is a side elevational view of the preferred form of my curling device showing a mandril mounted thereon.

Figure 3 is a sectional view taken along line 3—3 of Figure 2 showing the handle structure.

Figure 4 is a perspective view of my stretching device showing the handle and the winding mandril as well as the gripping jaws.

Figure 5 is a sectional view showing the operation of my device with reference to a lock of hair held by the gripping jaws and being wound on the mandril.

Figure 6 is a perspective view illustrating my method of curling the hair with my curling device.

Referring more particularly to the drawing, I disclose a hair curling device generally indicated by the numeral 1 which is provided with a handle portion on one end thereof and gripping jaws disposed on the opposite end. The handle portion consists of two parts, 2 and 3, which are assembled together in a manner to be described. The handle part 2 interfits into the handle part

2 as best shown in Figures 1 and 3 and is held in place by means of retaining pins 4 which extend through the handle parts 2 and 3. The pins 4 extend through slots 4a formed in the handle portion 3 as shown best in Figures 1 and 3. Thus, when the parts 2 and 3 are squeezed together the pins 4 will move freely in the slots 4a, thereby exerting an even pressure relatively horizontally throughout the length of the handle. The handle members 2 and 3 are normally spaced apart as shown in Figure 1 by means of the spring members 5 that are secured to the inner wall of the handle part 2 by means of screws 6. The outer ends of these springs 5 are provided with turned up portions 5a that bear against the inner side wall of the handle member 3. When the parts 2 and 3 are squeezed together the springs 5 tend to flatten or bow out and when the pressure is released they return to normal position as shown in Figure 1. I preferably show a series of retaining pins 4 which aid in guiding the handles 2 and 3 evenly when pressure is exerted thereon, thus eliminating any sticking action that may occur. Two springs 5 are shown within the handle but more or fewer can be used depending on the structure of the handle.

The ends of the handle members 2 and 3 are provided with a pair of jaw members 7 and 8 which form the hair gripping members that are moved horizontally toward each other when the handle members 2 and 3 are compressed. The jaw members 7 and 8 are provided with a knurled inner gripping surface 9 which tends to grip the hair. The member 7 is solid and square in cross section as best shown in Figure 5 while member 8 is channel formed as best shown in Figure 1. Jaw member 8 is provided with a movable member 10 supported therein so that it can be moved inwardly in the channel portion of the jaw 8 if excessive pressure or if an uneven amount of hair is fed between any portion of the jaw members 7 and 8. This moving action is accomplished by means of spring members 11 which are suitably mounted and spaced on the member 10, as best shown in Figures 1 and 5. The jaw member 8 being channel shaped allows the excessive pressure to be absorbed by the springs 11 as shown in Figures 1 and 5. This moving action is necessary in order that if a lock of hair of ununiform or uneven thickness is drawn between the member 7 and the member 10 there will be an even gripping action on the entire lock of hair. Thus, the springs 11 will also force the moving member 10 outwardly when part of the strand of hair is thinly distributed. One of the main disadvantages of prior art winders was due to the structure of the gripping member. Anyone skilled in the art will readily understand the utility of my new structure. Jaw member 7 is provided with two forked members 12 that are adapted to hold the mandril 13 while the hair is being wound thereon. This mandril is supported in the usual manner and has a winding key 14 on its outer end. A swinging tongue member 15 is pivoted to the mandril and the outer ends of the hair are first clamped beneath the tongue member preparatory to the winding operation. As shown in Figures 5 and 6 I employ a scalp clamp protector 16 of the usual type to which the winder is affixed when the hair is wound up close to the scalp.

Having thus described the details of my curling device with reference to Figures 5 and 6, I will describe the operation and method of using the same. The hair is first treated with a soft-

tening solution and the scalp protector clamp 16 is suitably positioned at the scalp as shown in Figures 5 and 6. The hair is drawn through the jaw members 7 and 8 and is clamped into position on the mandril 13 between the swinging tongue member 15. The clamping jaws 7 and 8 are then tightened by means of the handle of the device and the hair is held securely at the point 9 while the winding mandril is turned by means of the key 14. It will be apparent that the hair is stretched between the gripping portion 9 and the mandril 13. After the hair is sufficiently stretched the pressure on the handle member is partly relieved, more hair is then pulled through the jaws and then again tightened so that another stretching operation will take place between the point 9 and the mandril 13. It will be noted from Figure 5 that there is absolutely no pressure on the scalp during this stretching operation since the gripping action takes place at the point of the gripping jaws. Thus, I stretch the hair many times in the manner set forth above by using a conventional mandril mounted on the gripping jaws as previously indicated. After the hair is stretched and wound on the mandril up to the clamp 16 the mandril is removed and placed in the holder of the conventional type shown in Figure 5 and heat is then applied in the usual manner. Because of the hair being stretched throughout it will not be necessary to apply heat as long as in present day waving. I have found that stretched hair curls more readily and permanently and with less heating time to curl it. It will be seen that I provide a method and apparatus for curling and stretching hair throughout which has not to my knowledge been done in the past and further which will reduce the amount and strength of the softening solution as well as considerably reduce the heating time required for curling hair. It is understood that my apparatus can be used on all types of waves, including machine, machineless, and the wave known as the cold wave.

Having thus described my invention, what I claim is:

1. A hair stretching device of the type described comprising a two-piece movable handle and a pair of gripping jaws disposed on one end of each of said handle portions, means for normally holding the gripping jaws in spaced relation to each other, said means comprising spring members mounted in said handle, said gripping jaws adapted to be closed by pressure exerted on the handle members so as to firmly grip a lock of hair passed therebetween, a rotatable winding mandril mounted on one of said jaws, said rotatable winding mandril having means for gripping the hair so that the hair may be stretched from the point of the gripping jaws and said mandril.
2. A hair curling device of the type described having gripping members disposed at one end and a handle disposed at the other end, said handle being of two-part construction and having spring members mounted therein for normally holding said gripping members away from each other, said gripping members adapted to be closed by pressure exerted on said handle members, said gripping members having uneven biting surfaces which will grip the hair positively, a rotatable mandril mounted on one of said gripping members and parallel thereto and having means adapted to grip the tips of the hair so that it may be stretched as it is being wound on the rotatable mandril.
3. A hair curling device of the type described comprising a handle member, gripping jaws dis-

posed at one end of said handle member, said handle being of two-part construction and having spring members mounted therein for normally holding said gripping members away from each other, said gripping members adapted to be closed by pressure exerted on said handle members, one of said gripping jaws being solid in cross section, the other said gripping jaw being hollow, means disposed within said hollow gripping jaw to take-up the gripping surface when an uneven amount of hair passes between said gripping jaws, a rotatable mandril mounted on one of said gripping jaws on which the hair is held and wound.

4. A structure according to claim 3 wherein said take-up means of the gripping surface comprises a pair of spring members mounted on the back of said gripping member which flatten out when an uneven amount of hair passes between said gripping jaws.

5. A curling device of the type described comprising a rotatable mandril, a pair of hair gripping jaws carried below and parallel to said mandril, a handle for actuating said jaws, said jaws being supported in opposing relationship at one end of said handle and being adapted to grip hair passed between said jaws, means on the mandril for holding the tips of the hair so that it may be stretched between the gripping jaws and the man-

dril and then wound on said mandril in such a manner that it will not pull the hair loose from the scalp.

6. A hair curling device of the type described comprising a pair of gripping jaws, a two-part handle member for supporting said jaws at one end thereof in opposing relationship, said jaws adapted to grip a lock of hair therebetween when pressure is applied to said handle to bring the jaws together, means disposed within said handle to normally maintain the jaws open, means disposed within one of said jaws to equalize the pressure when an uneven amount of hair is fed through said gripping jaws.

7. A hair curling device of the type described comprising an articulated handle, a pair of parallel gripping jaws supported at one end of said handle, means disposed within said handle for opening and closing said opposing jaws by pressure exerted on the handle member so as to firmly grip a lock of hair passed between said jaws, a rotatable winding mandril mounted on one of said jaws, said mandril being parallel to said gripping jaws and having means for gripping hair in order to stretch it between the gripping jaws and the mandril in such a manner that it will not pull the hair loose from the scalp.
